UNITED STATES PATENT OFFICE

JOSEPH BIRBAUM, OF WEST ALLIS, WISCONSIN, ASSIGNOR TO MILWAUKEE STAMPING COMPANY, OF WEST ALLIS, WISCONSIN, A CORPORATION OF WISCONSIN

HANDLE-CONNECTING TRIM MEMBER

Application filed September 18, 1929. Serial No. 393,370.

My invention relates to improvements in handle connecting trim members or journal members which receive the swing loops of the handles of traveling bags and other receptacles.

The object of my invention is to provide simple and inexpensive means for preventing the swing loop from shifting in its bearings.

10 The swing loops ordinarily employed to connect the handles of baggage receptacles with the trimming on the bag frame, are usually of the split ring type having straight extremities axially aligned and journaled in suitable pivot bearings formed in the trim. The handle connecting trim members ordinarily comprise sheet metal stampings having prongs which extend through slots in one of the bag frame members to be clinched 15 or riveted on the inner side and these bearings have heretofore been open on the inner side except at the ends of the trim member, thereby allowing the swing loop to shift to a position where it cramps in the bearing and 20 fails to swing with the handle from position of use to one of non-use, etc.

It is my object to so construct the trimming that it will prevent shifting movements of the swing loops in their own plane without 25 adding to the expense of construction or impairing the appearance of the trim member.

In the drawings:

Figure 1 is an isometric view of a suit case to which my invention has been applied.

30 Figure 2 is a sectional view of one of the trim members, drawn to a plane through the axis of the swing loop bearing and showing fragments of an associated swing loop.

Figure 3 is a plan view of the trim member with the outer wall of the bearing and the major portion of the swing loop broken away.

Figure 4 is a view taken at right angles to Figure 2.

45 Figure 5 is a view similar to Figure 2, showing a modified form of swing loop.

Like parts are identified by the same reference characters throughout the several views.

50 My improved trim member may be of

ordinary construction except as hereinafter described, and it is secured to the lock side band 10 by clinching prongs 11 which pass through slots in the band, in accordance with ordinary practice. The body portion of the trim member comprises a hollow shell 12 having a central portion struck up to form a generally semi-cylindrical bearing member 13. Heretofore it has been customary to punch openings 14 in the end walls 15 of this upwardly offset or struck up portion into which the extremities 16 of the swing loops may be inserted.

Instead of removing the material through which these openings 14 are punched, I simply sever such material on three sides from what may be termed the end wall 15 of the offset portion and bend this partially severed material inwardly to form a lip 17, preferably of the contour shown in Figure 3. This provides an opening 14 into which the end of the swing loop may be inserted, and the lip 17 forms a bearing for the inner side of the inserted portion of the swing loop.

By thus forming the apertures 14 at each end of the bearing and bending the partially severed material inwardly to form lips 17, I am able to nearly bridge the space between the apertures on the inner side of the bearing, and thus provide a substantially closed, 75 semi-cylindrical or nearly tubular bearing member in which the straight end portions 16 of the swing loop may be journaled. The lips 17 prevent the elbowed or bent portions 19 of the swing loop from entering the bearing because the distance between the lips 17 and the outer wall 13 is substantially equal to the diameter of the wire or rod from which the swing loop is formed and, therefore, a bearing having the lips 17 will receive only those portions of the swing loop, the axes of which coincide with the axis of the bearing.

It is, therefore, obvious that the bearing will not receive the arcuate portions 20 or 21 of a swing loop having the contour illustrated in Figure 2 and it will also appear from Figure 5 that a swing loop having its major portion 22 constructed in the form of a true circle will have its extremities 16^a 95 100

securely anchored in the bearing of the trim member for the reason that the lips 17 of the trim member provide a substantially straight line or multiple bearing points on the inner side instead of the two points heretofore provided merely on the inner sides of the apertures 14.

I claim:

- 10 1. A connecting trim member for receptacle handles composed of sheet metal having a portion offset in a generally semi-cylindrical form to form the outer wall of a bearing member and having the end walls of the offset portion partially severed except at the inner side and inwardly turned to form lips adapted to serve as an inner wall for the bearing member.
- 20 2. A connecting trim member for receptacle handles comprising a sheet metal shell having a portion offset to form the outer wall of a bearing member and having the ends of the offset portion provided with openings from the inner side of which lips extend inwardly from each end underneath the outer wall of the bearing at a distance from such outer wall substantially equal to the diameter of the member to be journaled in said bearing.
